E. CARR

WATER HEATER

Filed July 23, 1923

Inventor:

Edward Carr
By *Paul Daniels*
Attorney

UNITED STATES PATENT OFFICE.

EDWARD CARR, OF AUCKLAND, NEW ZEALAND, ASSIGNOR OF NINE-SIXTEENTHS TO
HARRY DELAMERE DANSEY, OF AUCKLAND, NEW ZEALAND.

WATER HEATER.

Application filed July 23, 1923. Serial No. 653,346.

To all whom it may concern:

Be it known that I, EDWARD CARR, subject of the King of Great Britain, residing at East Coast Road, Milford, Auckland, 5 Dominion of New Zealand, have invented a new and useful Water Heater, of which the following is a specification.

This invention relates to a water heater of the type in which the heating agency for 10 the water consists in a circulatory system, such as a pipe circuit connected with a water chamber and passing through a heating zone of any of the known and approved classes generally used in these systems, as 15 for instance, around the burners of a gas stove, through the oven of such a stove, or through electrically heated appliances.

The invention consists in a special construction of appliance by which a tank is 20 formed having a heating chamber within its bottom, and a supply chamber in its top, divided off from one another by an insulating air space or chamber, such heating chamber being supplied from the supply chamber as 25 water is drawn off from it, so that it always remains full. The supply chamber may itself be kept full by any of the automatic means well known in the art, or may be charged by hand from time to time, as required. 30

The heating chamber is provided with a draw off tap leading from near its top and is connected up with the circulating pipe system in the usual way.

35 This construction is shown in the accompanying drawing, which is a general sectional elevation of the whole heater.

As illustrated, the heater is formed by a single structure of approved size and shape, 40 but preferably of the cylindrical urn like form shown. This is divided off in its height to form a large upper chamber A and a smaller lower chamber B at the bottom, and an intermediate air sealed chamber C 45 of relatively small area.

The upper chamber A is connected with the lower chamber B by means of a pipe D internally disposed and extending through from the bottom of the chamber A to near 50 the bottom of the chamber B. The lower chamber is provided with a draw off tap E opening from it at a point near its top.

Consequently when the supply chamber A

is charged with water, the chamber B will be filled through the connection D and will 55 be always kept full, as the withdrawal of water through the tap E, will result in water from the chamber A replacing that drawn off.

The chamber A is connected up by the 60 pipes F with the circulating heating unit of whatever class employed, such pipes being disposed to extend from the bottom and pass into the top of such chamber in the well known convection system, so that the 65 water in this chamber is heated thereby and may be drawn off from the top as required. The air space C then acts as an insulating space to protect the hot water in the chamber B at its hottest zone from loss of heat 70 by radiation and through actual contact with the cold water in the bottom of the supply chamber A.

The supply chamber A is provided with a removable top cover A' to allow for it being 75 filled by hand, as required. Or it may be connected to a storage tank through a connection H and the supply automatically maintained by any of the automatic controls employed in the art. 80

A vent pipe G is provided to extend up from the top of the chamber B, through the chamber A to above the water level therein. This will allow for the escape of any steam generated in the heating chamber and for 85 the overflow of any ebullition of water, into the said chamber A.

I claim:—

A water heater formed by a vessel divided off to provide a supply chamber in the top, 90 a heating chamber in the bottom, and an air chamber situated between them, such heating chamber being connected to a water heating circulatory system, a pipe connection extending from the bottom of the supply chamber to near the bottom of the heating chamber, and a draw off tap opening from the top of the heating chamber, substantially as specified. 95

In testimony whereof, I affix my signature. 100

EDWARD CARR.
